COLLAPSIBLE CLOTHES HANGER

Leo C. Fowler, Jackson Heights, N. Y.

Application October 21, 1946, Serial No. 704,628

3 Claims. (Cl. 223—83)

1

This invention relates to clothes hangers and more particularly to a clothes hanger of the foldable type.

It is an object of the present invention to provide a clothes hanger which may be folded into a compact package for transport in the suitcase of the traveler and which can with little effort be unfolded to form a hanger ready for use.

It is another object of the invention to provide a foldable clothes hanger which when folded will be retained in its folded shape by the hook portion which is folded into the package and which frictionally engages with the folded parts to hold them against separation until the hook is drawn out of the package.

According to the invention, the arm portions of the hanger are hinged together at the top so as to be folded downwardly and brought together. When in their up position and extended to support a garment they are held by trouser bar portions which are separable from one another when folding the hanger and adapted to be pivoted into and under the respective arm portions to hold them in their folded positions. A clip joins the inner ends of the trouser bar portions when the hanger has been opened for use. In one form a hook which is connected to the hinge pin joining the two arm portions may be slid into slots into one of the arm portions which are slightly offset to the vertical plane in which the hook is swung so that the side of the hook will engage with frictional contact with the side of the slot thereby retaining the hook until such time as force is applied to break the frictional engagement of the hook with the side of the slot. In another form of the invention, the hook extends through slots in both arm portions whereby to hold the arm portions by friction against separation as well as to maintain the hook in place.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a front elevational view of the hanger with the arm portions extended and the hook in its upright position.

Fig. 2 is an end elevational view of the hanger shown in Fig. 1.

Fig. 3 is a top plan view of the hanger shown in Fig. 1.

2

Fig. 4 is a vertical cross sectional view taken along the line 4—4 of Fig. 1, looking in the direction of the arrows thereof.

Fig. 5 is a transverse cross sectional view of the hanger taken along the line 5—5 of Fig. 4, looking in the direction of the arrows thereof.

Fig. 6 is a side elevational view of the hanger after the trouser bar portions have been folded in and the arm portions folded together.

Fig. 7 is a cross sectional view of the folded hanger showing the hook engaging with the slots of one arm portion and the trouser bar thereof.

Fig. 8 is a fragmentary front elevational view of a clothes hanger of a modified form having a hook of different shape, adapted to extend through slots in both arm portions.

Fig. 9 is a fragmentary cross sectional view taken in the region of the catch for retaining the trouser bar portions in their extended positions.

Fig. 10 is a fragmentary cross sectional view taken through the folded hanger showing the hook engaging with slots in both arm portions.

Fig. 11 is an enlarged fragmentary view looking in plan upon the slide catch of one of the trouser bar portions having a slot for receiving a hook.

Referring now to the figures, 15 represents a clothes hanger comprising side arm portions 16 and 17 connected together by hinge elements 18 and a pin 19 extending through the elements. Upon this same pin 19 there is connected a hook 21 for pivotal movement. On the lower ends of arm portions 16 and 17 and internally thereof, there is pivoted respectively trouser bar portions 22 and 23 as by pivot pins 24. These bar portions 22 and 23 are of channel shape and can fold into the arm portions 16 and 17 which are also of channel shape.

When the bar portions are down their rounded rear ends 25 will engage the rounded inner faces of the arm portions and be retained against downward movement beyond their horizontal positions. One of the bar portions has a slide 27 with a handle 28 whereby upon moving the slide through a strap 29 on the trouser bar portion 22 the parts will be positively held in horizontal alignment.

To collapse or fold the hanger for transport the latch 27 is withdrawn from under the strap 29 and the trouser parts are folded into the arm portions. This will permit the arm portions to be folded together about the hinge pin 19. The hook 21 is then pivoted into a top end slot 31 of the arm portion 16 and into a slot 32 of the arm por-

tion 16 and slot 33 of the trouser bar portion 22. Both of these slots 32 and 33 are offset from the center of the hanger or the plane in which the hook 21 is pivoted so that the hook must be slightly forced to the side in order to enter the slots whereby to place the hook in frictional engagement therewith so that it will be retained against easy removal from the slots. By having the hook so located when the hanger is folded it can be easily removed from the suitcase without hooking upon articles which may be contained in the suitcase.

Referring now particularly to Figs. 8, 9, 10 and 11, it will be noted that there is provided a hook 35 having nearly a complete circular formation 36 thereon. In addition to slots being provided in the arm and bar portions 16 and 22 there are provided similar slots 37 and 38 in the arm and bar portions 17 and 23. A slide 39 for retaining the trouser bars together also has a slot 41 for receiving the circular portion 36 of the hook and like the slots 32, 33, 37 and 38 is also offset from the center of the hanger and the vertical plane in which the hook is pivoted. Thus the hook will have frictional engagement with the parts at both sides of the hanger whereby it will not only hold the hanger in place but will also provide to some degree a locking means for retaining the parts in their folded position so that they will not rattle or separate from one another.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A collapsible clothes hanger comprising two arm portions hinged together at their top ends and having opposed free ends, said arm portions being laterally foldable toward one another to collapse said hanger, a trouser bar portion piv-

totally connected to each of said free ends for movement into and out of said arm portions, a hook pivoted on said hinge connection of said arm portions and adapted to be pivoted into a vertical plane, each of said arm portions and their respective trouser bar portions having a slot formed therein, said slots of each arm portion and its associated bar portion being aligned when each associated bar portion is pivoted into its respective arm portion, all of said slots being aligned when said arm portions are folded toward one another whereby said hook may be pivoted and received therein.

2. A collapsible clothes hanger as defined in claim 1, said slots being offset to cause said hook to exert lateral latching pressure on said arms and their associated trouser bar portions.

3. A collapsible clothes hanger as defined in claim 1, and catch means for securing said trouser bar portions together in their extended positions, said catch means comprising a slide adapted to be moved into engagement from one of said trouser bar portions with the other trouser bar portion, said slide having a slot formed therein which is aligned with the slot formed in its associated trouser bar portion when its associated trouser bar portion is folded into its respective arm.

LEO C. FOWLER.
